UNITED STATES PATENT OFFICE

GEORGE H. WHITTINGHAM, OF BALTIMORE, MARYLAND, ASSIGNOR TO MONITOR CON-
TROLLER COMPANY, OF BALTIMORE, MARYLAND, A CORPORATION OF MARYLAND

COMPENSATING THERMOSTAT

Application filed July 19, 1928. Serial No. 293,892.

This invention relates to a compensating thermostat adapted to be operated by electric current. More particularly, the invention comprises means for insuring accuracy in the operation of the thermostat at all atmospheric temperatures, and structural details which make the device inexpensive to manufacture.

In the accompanying drawing,

Fig. 1 is a front view of the thermostat, the enclosing tube being shown partly in central section;

Fig. 2 is a side view of the thermostat, the tube being shown in central section;

Fig. 3 is a cross section on the line 3—3 of Fig. 1; and,

Fig. 4 is a section on the line 4—4 of Fig. 2.

The thermostat comprises a flat strip 1, of insulating material, having the operating elements secured to its opposite ends, and a tube 2, of insulating material, fits closely around the side edges of the strip, the latter forming a partition which divides the interior of the tube into two compartments. A sheet metal clip 3, of U-form, fits over one end of the strip, and this clip or fitting has feet 3^a for attachment to a suitable base 4, and it also has outwardly turned ears 3^b and 3^c which are perforated to receive a pivot pin 5, which lies in the plane of the strip 1. A flat metal strip 6 has flanged ends 6^a perforated to receive the pin 5, and this strip is adapted to rock about the pin. This rocking member has a boss 6^b at one end into which the pivot pin extends, and a contact arm 7 is adjustably mounted upon the boss. As shown, the contact arm is split at one end, and this end is provided with a clamping screw 8, for clamping the contact arm to the boss. A cross-arm 9, of insulating material, is centrally mounted upon the rocking member 6 and extends at right angles to said member and to the pivot pin.

Binding posts 10 and 11 are secured to the opposite ends of the cross-arm and to these binding posts are secured thermally expansible wires 12 and 13, respectively, which wires are secured at their opposite ends to a rod 14, which is slidably mounted in a U-shaped bracket 15, the latter being secured to the end of the supporting strip 1, which is oppo-

site the cross-arm. This rod lies and moves in the plane of the supporting strip, the latter being recessed, as shown at 16, to receive the rod. A spring 17, surrounding the rod, is interposed between a washer 18 on the rod 55 and one arm of the bracket 15, the spring and rod constituting a tensioning device for keeping the thermally expansible wires taut. A split metal bar 19 fits over and is secured to the lower end of the strip 1, and the bracket 60 15 is riveted to this bar. The bar has an opening 20, to receive a binding post 21, which is mounted on the base 4.

The tube 2 is detachable and it is provided with a notch 2^a at one end so that it may 65 pass upwardly around the fitting 3 to the end of the supporting strip 1.

A flexible conductor 22 electrically connects the sliding rod 14 with the bar 19 which is electrically and mechanically connected with 70 the binding post 21. Thus, the expansible wires are electrically connected to said binding post. A flexible conductor 23 is shown connected to the wire 13, and this conductor passes through a perforation in the cross-arm 75 9. If it is desired to use the expansible wire 12 as part of an electric circuit, a flexible conductor will be connected to the upper end of the latter wire.

In operation, the contact arm 7 is set in 80 any desired normal position while the expansible wires are at atmospheric temperature, and the arm will not be shifted from normal position except when an electric current is passed through one of the wires as, for instance, the wire 13. When this wire is heated by the current it will expand and the tension device, pulling upon the other wire, will cause the cross-arm to rock and move 85 the contact lever. It will be obvious that the 90 device will not be affected in its operation by changes in atmospheric temperature. The strip of insulating material which supports the operating parts of the thermostat forms a partition in the tube which keeps 95 the heat from the wire through which the current is passing from affecting the wire on the opposite side of the partition, and the tube which encloses both wires shields the 100 wires from drafts of air which might other-

wise affect the temperatures of the wires unequally.

What I claim is:

1. A thermostat comprising a flat strip of insulating material, a cross-arm pivotally mounted upon one end of the strip and projecting at opposite sides of the strip, a rod at the other end of the strip mounted to slide longitudinally thereof, a spring urging said rod away from the cross-arm, and thermally expansible wires connecting said rod with opposite ends of the cross-arm.

2. A thermostat comprising a flat strip of insulating material, a cross-arm pivotally mounted upon one end of the strip and projecting at opposite sides of the strip, a rod at the other end of the strip mounted to slide longitudinally thereof, a spring urging said rod away from the cross-arm, thermally expansible wires connecting said rod with opposite ends of the cross-arm, and a tube enclosing the strip and wires.

3. A thermostat comprising a flat strip of insulating material, a metal part secured to one end of the strip and having bearings in the plane of the strip, a rocking member pivotally mounted in said bearings, a contact arm adjustably mounted on said member, a cross-arm secured centrally to said member and projecting at opposite sides of the strip, a tensioning device mounted on the other end of the strip and comprising a spring-pressed rod slidable in the plane of the strip, and thermally expansible wires connecting said rod with opposite ends of the cross-arm.

In testimony whereof I affix my signature.

GEORGE H. WHITTINGHAM.
